UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR.

No. 914,242.

Specification of Letters Patent. Patented March 2, 1909.

Application filed July 13, 1908. Serial No. 443,250.

To all whom it may concern:

Be it known that I, ARGYLE CAMPBELL, a citizen of the United States, residing in Chicago, in the county of Cook and State of Illinois, have invented a new and useful Improvement in Dump-Cars, of which the following is a specification.

My invention relates to improvements in dump cars, and more particularly to the operating mechanism for dump car doors.

The object of my invention is to provide a dump car door operating mechanism of a simple, strong, efficient and durable construction, by which a plurality of doors may be simultaneously operated from the same operating shaft, and in which the doors will be held or locked securely in their closed position, and in which the load on the doors will have no tendency to unlock or release the door operating mechanism, and in which the strain of the locking or load supporting mechanism for the doors will be exerted upon opposite sides of the operating shaft so as to neutralize each other and thus exert no bending or side strain upon the operating shaft.

My invention consists in the combination with a plurality of dump car doors, of a common operating shaft for the several doors, a plurality of winding drums on said shaft, the same being preferably made in one piece, each having a flat and preferably shouldered locking face, the drums being polygonal and preferably four sided, a pair of locking blocks, each preferably having a shouldered face adapted to engage and interlock with the shouldered face of its drum, a plurality of connecting links between each locking block and its drum, the same being preferably three in number for each drum and fitting and corresponding to the three sides of the drum while the locking block fits and corresponds with the remaining side thereof, and supporting connections between the several doors and locking blocks, the locking faces on the two drums being arranged opposite to each other, so that the common operating shaft is embraced between the opposing forces of the doors acting against the locking blocks upon the opposite sides of the operating shaft.

My invention also consists in the novel construction of parts and devices, and in the novel combinations of parts and devices

herein shown and described and more particular specified in the claims.

In the accompanying drawing forming a part of this specification, Figure 1 is a plan view of a dump car embodying my invention. Fig. 2 is a side elevation. Fig. 3 is an enlarged vertical cross section on line 3—3 of Fig. 2. Fig. 4 is a detail plan view showing the common operating shaft and connecting links unwound from the drum. Fig. 5 is a side elevation of the parts shown in Fig. 4. Figs. 6 and 7 are detail sections on lines 6—6 and 7—7 of Fig. 4, but showing the locking blocks and connecting links in their locked or closed position. Fig. 8 is a detail plan view of the same. Fig. 9 is a detail perspective view of the winding drums, the same being made integral. Fig. 10 is a vertical cross section illustrating a modification.

In the drawing, 1 represents a dump car of any suitable kind or construction, 2 the intermediate sills, 3 the side sills, 4 the upper floor plates of the car. The dump doors 5, 5 and 6, 6 are preferably arranged in pairs, each pair having hinges 7 so that the swinging edges of both doors of each pair 5, 5 or 6, 6 come together. The doors may be arranged to swing open transversely of the car as shown in Figs. 1 and 2, or longitudinally as shown in Fig. 10. Both pairs of doors 5, 5 and 6, 6 are simultaneously operated by a common operating shaft 8 journaled in suitable supporting brackets 9 on the car frame and preferably arranged between the two pairs of doors 5, 5 and 6, 6.

The common operating shaft 8 is provided with two winding drums 10, 11, both preferably in one integral piece for convenience in manufacturing. Each of the winding drums 10, 11 is preferably of a polygonal shape and four sided, the two drums being preferably duplicates of each other. Each of the winding drums has a locking face 12, which is furnished with a shoulder 13. The locking faces 12, 12 of the two drums are reversely arranged so that they come on diametrically opposite sides of the common operating shaft 8, as will be readily understood from Figs. 4 to 9. Each of the winding drums 9, 10 is also furnished with a pivot lug 14, and also with guides or flanges 15 for receiving the connecting links of the door operating mechanisms as the same wind

around the drum. Connected to the pivot lugs 14, 14 are connecting links 16, 16 and locking blocks 17, 17, the locking blocks having each a locking face 18, preferably furnished with a shoulder 19 and adapted to engage the locking faces of the winding drums when the connecting links are wound around the drum. Each set of connecting links 16 are preferably three in number, and 5 with the locking block thus correspond to the number of faces of the winding drum. The pivot lugs 14, 14 on the two winding drums are located diametrically opposite each other so that the two locking blocks 17, 17 thus 10 come on the horizontal center line of the common operating shaft and so that the strain or load of the dump doors exerted by the two locking blocks against the two winding drums oppose each other on opposite sides of the 15 common operating shaft and thus produce no tendency to bend the shaft or to cause its bearings to give way.

The locking blocks 17, 17 have connections 20, 20, extending the one to one pair of doors 25 5, 5 and the other to the other pair of doors 6, 6. As illustrated in Figs. 1 to 9, the connections 20 are represented as chains or flexible connections and are furnished with branches 21, 21 extending to each door of 30 each pair. The chains or connections 20 extend over guide pulleys 22. The common operating shaft 8 is furnished with an operating lever 23 and ratchet 24.

The dump car door operating mechanism 35 is preferably duplicated at each end of the doors 5, 5 and 6, 6 as will be readily understood from the drawings.

In the modification illustrated in Fig. 10, the invention is shown as applied to a side 40 dump coke car, the doors 5^a and 6^a being longitudinally instead of transversely hinged. In this modification, the connections 20^a between the locking blocks and the swinging edges of the doors are represented as being 45 rods instead of chains. The operating mechanism illustrated in this figure is the same as above described. The locking face 18 of each of the locking blocks 17, 17 extends for its major portion past the center line of the 50 shaft when the doors are closed and the locking mechanism in locked position, so that the

load of the doors has no tendency to turn the shaft in the door releasing direction.

I claim:

1. In a dump car, the combination with a 55 plurality of load supporting doors, of a common operating shaft, a pair of winding drums on said shaft each having a locking face, the locking faces of the two drums being on opposite sides of the shaft, a pair of locking 60 blocks having locking faces engaging the locking faces of the drums on opposite sides of the shaft, flexible connecting links between each drum and each locking block, and connections between the locking blocks and the 65 doors, substantially as specified.

2. In a dump car, the combination with a plurality of load supporting doors, of a common operating shaft, a pair of winding drums on said shaft each having a locking face, the 70 locking faces of the two drums being on opposite sides of the shaft, a pair of locking blocks having locking faces engaging the locking faces of the drums on opposite sides of the shaft, flexible connecting links between each drum and each locking block and connections between the locking blocks and the doors, said locking faces on the drums and locking blocks being furnished with inter-engaging shoulders, substantially as specified. 75

3. In a dump car, the combination with two load supporting doors, of a common operating shaft, a pair of winding drums on said shaft, a pair of locking blocks on opposite sides of the shaft and connected with 80 the doors so that the shaft is clamped between said locking blocks by the doors, substantially as specified.

4. In a dump car, the combination with 90 two doors, of a common operating shaft, and locking devices on opposite sides of the shaft connected to the doors, each of said locking devices having a locking face extending for its major portion past the center line of the shaft so that when in closed and locked position, the load of the door has no tendency to 95 turn the shaft in the door releasing direction, substantially as specified.

ARGYLE CAMPBELL.
